UNITED STATES PATENT OFFICE.

ROBERT H. WENTORF, OF WEST BEND, WISCONSIN, ASSIGNOR TO WEST BEND ALUMINUM COMPANY, A CORPORATION OF WISCONSIN.

VALVE FOR COOKING VESSELS.

Application filed December 12, 1921. Serial No. 521,802.

The invention relates to escape valves, and is more particularly directed to that class of valves used for cooking vessels, such as boilers or steamers and has for its primary 5 object the provision of an automatic poppet valve to be placed in the cover of a boiler to relieve the pressure of steam within the boiler.

A further object of the invention is to 10 provide such a valve which is simple in construction and has few parts and is economical of manufacture.

The invention is more particularly applicable to that class of steamers or boilers having a cover with what is known as a steam 15 tight fit.

Other objects of the invention will appear from the following description, which is directed to the preferred embodiment of the 20 invention, reference being made to the accompanying drawing forming a part of the specification, in which—

Fig. 1 is a top plan view of a boiler cover showing my invention applied thereto.

25 Fig. 2 is a vertical sectional view taken on line 2—2 of Fig. 1 showing the valve in closed position.

Fig. 3 is a fragmental sectional view of 30 Fig. 1 taken on line 2—2 showing the valve in open position.

Fig. 4 is an enlarged detail view of the assembled valve.

Fig. 5 is an enlarged detail view of the stem of the valve.

35 Fig. 6 is an enlarged detail top plan view of the lower portion of the valve with the stem removed therefrom.

Referring now to the drawings for a more 40 particular description of my invention, the reference character 10 represents a cover for a boiler having a downwardly struck spherical concavity 11 in the approximate center thereof which has aperture 12 therethrough and concentric with concavity 11, through 45 which aperture stem 13 is adapted to have reciprocal movement, there being a clearance between the periphery of aperture 12 and stem 13 for the escape of steam from the boiler when the valve is in open position, as 50 shown in Fig. 3. Stem 13 carries at its upper end a spherical closure member 14, which is adapted to seat within the concavity 11 and close aperture 12 when in closed position, as shown in Fig. 2. A weight 15 is 55 carried by the lower end of stem 13 to retain

the valve in closed position until such time as the pressure of steam within the boiler is sufficient to raise the weight 15 by the pressure of the steam on the lower face of closure member 14 intermediate the periphery 60 of aperture 12 and valve stem 13. Weight 15 carries a plurality of upstanding spacing members 16 which spacing members are adapted to contact with the underside of cover 10, thereby limiting the upward movement of the closure member 14 with relation to the cover 10. The weight 15 may of course be made of any suitable material and of such shape and contour as may be deemed desirable, though I prefer to form this 70 weight in the shape of a hemisphere, as shown in the drawings.

In assembling my improved valve with the cover of a boiler I insert stem 13 downwardly through aperture 12 in the cover and 75 through central bore 17 in the weight 15 when the end of the stem may be flared in any suitable manner, as shown at 18, Fig. 4.

Having thus described my invention, what I claim is:

1. The combination with the cover of a boiler having a concavo-convex portion formed from the material of said cover, a spherical closure member adapted to seat in the concavity of said portion, a stem carried by said member, a weight carried by the inner end of said stem, and spacing members carried by said weight and normally spaced from the inner side of said cover.

2. The combination with the cover of a 90 cooking vessel having a concave spherical portion formed integrally with the cover and extending toward the interior of the vessel with an aperture through the cover of the vessel at the center of the downwardly 95 formed spherical portion, the said aperture cutting away only a portion of the said downwardly formed spherical portion, a spherical closure member adapted to seat in said downwardly formed spherical portion, a stem secured to the closure member and being adapted to be reciprocably carried in the said aperture, and a weight carried by the lower end of said stem for normally seating the closure member on its said seat to 100 form a substantially vapor tight closure.

3. The combination with the cover of a 105 boiler having an aperture therethrough with a valve seat surrounding said aperture formed by having the material of the cover 110

surrounding the aperture pressed downwardly in the general form of a segment of a sphere, a closure member for said spherical valve seat having a co-operating surface 5 in the form of a segment of a sphere, a stem connected with said closure member and being adapted to press downwardly through said aperture, and a weight carried by the

lower end of said stem and being adapted to hold said closure member normally in contact with said valve seat to close the valve.

In testimony whereof I have signed my name to this specification on this 30th day of November, A. D. 1921.

ROBERT H. WENTORF.
